UNITED STATES PATENT OFFICE.

HENRY RIDGEWAY HART, OF MONTCLAIR, NEW JERSEY.

PLAYING BALL.

Application filed January 11, 1922. Serial No. 528,433.

To all whom it may concern:

Be it known that I, HENRY RIDGEWAY HART, a citizen of the United States, residing at Montclair, in the State of New Jersey, have invented certain new and useful Improvements in Playing Balls, of which the following is a specification, reference being had to the accompanying drawing, forming a part hereof.

10 This invention relates to the type of football, basket ball, punching bag and other playing devices in which a valve is secured to the bladder. The description herein will be, by way of example, with particular reference to a football, but it is to be understood that the invention and claims are not to be limited to the particular playing device.

20 The principal object of the invention is to provide a valve tube of improved structure, and also improved means for securing the valve tube to the bladder, these improvements resulting in a simple and thoroughly practicable commercial structure which may be 25 manufactured and applied to bladders at a reasonable cost. In accordance with the invention it is proposed to finish off the bladder with a plain hole to receive the valve tube and to provide a special valve tube 30 which shall be formed with retaining devices adapted to co-operate with the rubber of the bladder in such manner as to clamp the valve tube securely to the bladder and effect 35 an air-tight engagement therebetween. Still another object is to reduce the over-all dimensions of such devices to a point where bulging is entirely eliminated and to associate with the valve tube a closing cap whose 40 head shall be of such form and dimensions as to satisfy the last named requirement and to facilitate the lacing of the cover 45 thereover. These and other objects will appear more particularly hereinafter in connection with the detailed description of the embodiment illustrated in the drawing, wherein—

50 Figure 1 is a view in plan of an inflated football embodying the invention, the head of the valve cap being indicated in dotted lines.

55 Figure 2 is a detail view in section and on a somewhat larger scale showing the relation between the bladder, the valve tube and the cover, and taken on the plane indicated by the line 2—2 of Figure 1 and looking in the direction of the arrows.

Figure 3 shows in perspective the valve tube with the clamping nut and washer by which it is united with the bladder, and also the valve cap.

It is understood, of course, that it is not new to provide a football bladder with a valve to the end that it may be inflated readily and the air retained when the pump is removed, nor is it new to lace the cover 60 up over the valve cap. It is true, however, that proposals heretofore made for accomplishing this desirable condition have been addressed to devices which have not been practical, either because of manufacturing 65 difficulties, expensiveness or deficiencies in use. In accordance with the present invention it is proposed to provide a simple, inexpensive and thoroughly practicable valve tube and connection therefor, which may be 70 readily clamped to the bladder with an air-tight union and be closed by a cap which is of such form as to rest without bulging under the laced cover. As indicated in Figure 2, the bladder *a* is of usual form 75 in every respect except that it is formed with a plain hole *a'* therein of such dimensions as to the receive the upper threaded end *b* of the valve tube *b'*. The end of the stem of the valve is indicated at *c*, but 80 this invention is not concerned with the interior valve structure but only with the character of the tube and the means for securing it to the bladder. The tube *b'* carries or has formed integral therewith a 85 rimmed flange *b*² which, when the valve tube is in place, lies against the inner wall of the bladder *a* immediately around the hole *a'*. A slightly flexible washer *d* of metal or other suitable material is adapted 90 to fit down over the threaded end *b* of the valve tube and overlie the outer surface of the bladder *a* immediately around the hole *a'*. This washer *d* may also be formed with a rim *d'* for engagement with the 95 yielding rubber of the bladder *a*. The clamping means is found in a nut *e* which may be threaded down on to the threaded end *b* of the tube and squeeze the rubber of the bladder between the rimmed flange *b*² and 100 the washer *d*. Holes *e'* may be formed in the nut *e* for engagement by a spanner wrench. It will be noticed that the threaded end *b* of the valve tube is made as short as 105 can be for the purpose intended, that is to say, it is only long enough to permit the nut *e* to be threaded down to clamp the rub-

110

ber on the flange b^2 , at which time the head 5 of the nut e is preferably about flush with the end of the threaded section b . This relation is, of course, all in the interest of compactness so that no undue bulging of the ball at this point will result. It will be noted further that the rim on the flange b^2 and the rim d' on the washer d are pressed into the rubber so as to squeeze it in such 10 manner as to form an air-tight union by purely mechanical devices. So far as is known it has never been proposed heretofore to squeeze the rubber by mechanical devices which themselves are separable to 15 an extent sufficient to form an airtight union. The construction described is not only inexpensive to manufacture but lends itself readily to assembly and removal for replacement of parts. While a washer d 20 has been illustrated it will be understood that under some conditions it will not be necessary since the squeezing action desired might be effected without employing such a washer.

25 The threaded end b is threaded interiorly also, as at b^3 , to receive the male stem f of a valve cap whose end f' is formed broad and flat but preferably with a slightly spherical finish. When this cap is threaded 30 down into the upper end of the valve tube it will be evident that the body of its head f' adds little in thickness to the devices protruding above the upper surface of the bladder a and that its spherical finish will 35 materially facilitate the lacing of the cover g over it, the edges of the cover adjacent to the laced opening g' being adapted to ride up the spherical head f' and bear thereon. A transverse slot f^2 may be provided 40 in the head for engagement by a coin or tool to assist in screwing the cap home. As

shown in Figure 2 the arrangement of parts is such that the exterior of the bladder a is nearly flush with the clamping nut e and so there is little danger of bulging of the cover over the valve. This is an end which must necessarily be sought for in a football.

Changes in details of construction and mere matters of design are to be deemed within the scope of the invention.

I claim as my invention:

1. In a playing ball, a bladder having an opening therein, a valve tube having a threaded portion extending through the opening and exposing a rimmed flange on the tube adapted to engage the inner side of the bladder adjacent the opening, a flexible rimmed washer through which the said threaded portion of the valve tube extends lying over the outer side of the bladder adjacent the opening, and a clamping nut threaded on the tube and forcing the flexible rimmed washer against the bladder to squeeze the latter against the flange and form an air-tight union.

2. In a playing ball, in combination with the cover and bladder having a hole therein, a valve tube extending through the hole, relatively movable devices associated with the valve tube to squeeze the rubber between the devices and clamp the tube in place with an air-tight union, the clamping device outside of the bladder lying nearly flush therewith and with the end of the valve tube, when in place, and a metal valve cap threaded into the end of the valve tube and having a broad flat head shaped spherically to lie under the cover of the football.

This specification signed this 9th day of January, A. D. 1922.

HENRY RIDGEWAY HART.
